UNITED STATES PATENT OFFICE.

JOHN P. WHITMORE, OF SOUTH PASADENA, CALIFORNIA.

ART OF MAKING PAINTED SHADE MATERIAL.

1,341,956.

Specification of Letters Patent. Patented June 1, 1920.

Application filed October 6, 1919. Serial No. 328,723.

To all whom it may concern:

Be it known that I, JOHN P. WHITMORE, a citizen of the United States, residing at South Pasadena, in the county of Los Angeles and State of California, have invented new and useful Improvements in the Art of Making Painted Shade Material, of which the following is a specification.

This invention relates to the manufacture of painted shade material for window shades, and particularly to the production of shade material of paper coated with suitable opaque paint such as is shown in United States Letters Patent No. 1,322,855, issued to me November 25th, 1919, and the main object of the present invention is to provide for rapid and economical manufacture of such paper window shade material in continuous lengths or rolls.

The accompanying drawings illustrate an apparatus suitable for carrying out my invention, and referring thereto:-

Figure 1 is a vertical section of such apparatus.

Fig. 2 is a horizontal section on line 2—2 in Fig. 1.

Fig. 3 is a horizontal section on line 3—3 in Fig. 1.

Fig. 4 is a partial elevation of the brushing means.

The apparatus shown in the drawing comprises means 1 for rotatably supporting a roll *a* of paper suitable for forming the body of the shade material, guide rollers 2, 3, 4 and 5 over which said paper is guided from said roll into a tank 6 containing a suitable paint and means for drawing the paper from said tank and maintaining it exposed to the air and under suitable tension in such manner as to insure drying of the paint and delivery of the paper in a smooth uniform roll. For this purpose I prefer to provide a drying tower 7 extending above paint tank 6 and having a feed roller 8 in its upper portion, over which the paper sheet or strip *b* passes, said strip passing under a roller 9 immersed in tank 6 and then upwardly through a vertical casing 10 and over roller 8, and then down to a suitable winding up roller or drum 11. The height of tower 7 should be sufficient to permit the paper to become substantially dry by the time it reaches the roller 11. To assist in such drying operation, a draft or current of air may be maintained in casing 10 by blower 12, having nozzles 13 discharging air upwardly

on each side of the strip *b* of paper. Suitable means such as doctor strips or blades 14 and 15 are provided for removing excess paint from the paper sheet, said means extending on opposite sides of the sheet directly above tank 6 and being preferably off-set so as to slightly overlap and produce a tension on the sheet. Brushes 16 and 17 are provided above the doctor blades on opposite sides of sheet *b* to smooth off the coating of paint, said brushes being preferably inclined reversely, as shown. Suitable means, such as motor 19 having driving connections 20 and 21 is provided for 70 rotating feed roller 8 and winding up roller 11, the connection to roller 11 being by slip belt or other slip connection to provide for the gradual increase in diameter of the roll as the paper is wound up on it. 75

In order to enable feed roller 8 to feed paper sheet *b* it is necessary to provide a presser or nip roller indicated at 25, rotatably mounted, for example, on a vertically swinging frame 26 so as to exert pressure 80 on paper *b* by the weight of said roller and frame, assisted, if necessary, by suitable spring means, 26'. I have found that there is a tendency for the paint to off-set or transfer from the paper *b* to the rollers 8 85 and 25 at parts which are subjected to such pressure, and to prevent this I provide a "dead-sheet" or parting strip 27 supplied from a roll 29 and passing between sheet *b* and roller 8, and a similar sheet or strip 28 90 supplied from a roll 30 and passing between sheet *b* and nip roller 25, said sheets 27 and 28 passing eventually to receiving means such as receptacles 32 and 33 in which they are folded or otherwise stored in condition for re-use. The parting strips 27 and 28 may be only as wide as the nip roller 25, which may extend over only the middle portion of paper sheet *b* and roller 8. A buffering roller 23 rotated by any suitable 100 means, may be provided for keeping roller 8 clean.

In case the apparatus is used for making paper shade material reinforced at the edges, I may provide a tape feeding device 105 at each edge of the paper sheet *b*, comprising feed rollers 35 feeding gummed tape *c* from a reel *d* to a moistening roller 36 from which the tape passes into contact with the paper sheet *b* against which it is pressed by 110 roller 37. If desired, a reinforcing thread or filament *e* may be supplied from a reel *f*

and pass between sheet *b* and each of the tapes *c*.

My process may be carried out in the above described apparatus as follows:—

5 The paper sheet *b* is drawn from roll *a* over guide rollers 2 to 5 and under roller 9 in tank 6, and then up through casing 10 and over feed roller 8 and then down to the winding up roll 11. In passing through 10 tank 6 the sheet *b* becomes coated on both sides with opaque paint, taken up from a body of paint indicated at *g* in said tank, the excess of paint being scraped off by the doctor blades 14 and 15 and smoothed off 15 by brushes 16 and 17. In passing up through casing 10 the paint becomes fairly dry, and in passing over the feed roller 8 and between said roller and the "nip" roller 25, it is separated from said rollers by the 20 "dead" sheets or parting strips 27 and 28 respectively, so that the paint does not offset on to said rollers, and the coat of paint is maintained in smooth uniform condition. In case the reinforcing tapes are to be applied 25 to the shade material, said tapes are drawn along with said material, after being moistened, and are pressed down on the shade material to adhere to same, the coating of paint being applied over said reinforcing tapes in obvious manner. The reinforcing threads *e* are applied at the same time and are held in place by the gum that holds the paper tapes *c* in position.

In some cases, particularly when glazed 35 paper is used for the parting strips 27 and 28, it is desirable to slightly moisten feed roller 8, for example by a wick 39 supplied with water by a pipe 40, so as to increase the grip of said roller on the paper.

40 What I claim is:—

1. The method of making shade material which consists in applying a coat of paint to each side of a continuous sheet, removing surplus paint therefrom, subjecting the 45 sheet to a drying operation, passing said sheet between moving surfaces exerting

pressure on same to feed the sheet forward, and passing a parting strip between said sheet and each of said moving surfaces to prevent offsetting of paint from said sheet 50 onto said surfaces.

2. In an apparatus for painting shade material, means for supplying a continuous sheet, means for applying paint to both sides of said sheet, means for removing surplus paint, a feed roller and presser roller adapted to engage the sheet to draw the same forward, said rollers being sufficiently removed from the paint applying means to enable partial drying of the sheet before 60 reaching the said rollers, and means for supplying a parting strip between said sheet and each of said rollers.

3. An apparatus for making shade material, comprising means for supplying a continuous sheet, means for supplying and applying to said sheet at each edge thereof, a continuous gummed tape, means for applying paint to both sides of said sheet and over said tape, means for removing excess 65 paint from the sheet, and means for drawing the sheet continuously forward.

4. An apparatus as set forth in claim 3 and comprising in addition, means for feeding a reinforcing filament between said 75 sheet and said tape.

5. In an apparatus for painting shade material, means for supplying a continuous sheet, means for applying paint to said sheet, a feed roller spaced sufficiently from the paint applying means to permit of drying of the paint before the sheet passes to the feed roller and a presser roller adapted to press the sheet against the feed roller so as to cause the feed roller to draw the sheet 85 forward, and means for feeding a parting strip between said sheet and said presser roller.

In testimony whereof I have hereunto subscribed my name this 23rd day of September 1919.

JOHN P. WHITMORE.
